TANK VALVE

John T. McGrath, Libertyville, Ill.

Application November 23, 1934, Serial No. 754,416

4 Claims. (Cl. 4—41)

The present invention relates to tank valves and more particularly to a novel supply and flushing mechanism for a toilet, water-closet or the like, or wherever a flushing operation is desired.

Among the objects of the present invention is the provision of a novel supply valve and mechanism for operating the same whereby to more quickly and efficiently refill a supply tank after the flushing operation.

A further object of the invention is the provision of a novel float construction operable in an auxiliary receptacle or tank for opening and closing the supply valve.

Another object of the present invention is the provision of a novel muffler construction for the supply outlet whereby to silence the rush of water therethrough and into the tank.

A still further object is the provision of a novel construction of casting or base which not only forms a mounting for the secondary or auxiliary tank but also provides a concave seat for the ball valve.

Another object is the provision of novel adjusting means and mechanism for the stems of the ball and float valves whereby such stems may be mounted and maintained in perfect adjustment and alignment.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawing, and while I have shown therein a preferred embodiment, it is to be understood that the same is susceptible of modification and change, and comprehends other details, arrangements of parts, features and constructions without departing from the spirit of the invention.

In the drawing:

Fig. 1 is a view in vertical cross-section through a flush or supply tank and showing the novel invention, part in side elevation and part in vertical cross-section.

Fig. 2 is a top plan view of the novel invention.

Fig. 3 is an enlarged view in horizontal cross-section through the ballcock or valve.

Fig. 4 is a view in vertical cross-section through the novel adjustable rocker arm.

Referring more particularly to the disclosure in the drawing, the numerals 1 and 2 refer to

the base and a side or end wall of a supply tank for a toilet, water-closet or the like. In the base of this tank is suitably mounted a supply or intake pipe 3 having a coupling 4 leading from and connected to a usual water supply system, and a discharge pipe 5 of considerably greater cross-section or diameter leading to the bowl of the toilet or the like (not shown).

The supply or intake pipe 3 is connected to an elbow 6 by means of a union 7, the other end of the elbow being connected to a novel ballcock or valve 8. This ballcock or valve construction comprises a removable housing or casing 9 in which is positioned a renewable valve seat 10 seating at its lower end against a shoulder 11 in the casing 15 and maintained in position by means of a hollow body or sleeve 12 provided with a series of discharge openings 13 around its periphery. This sleeve is locked in position by means of a packing box nut 14 threaded on the one end of the housing or casing and enclosing suitable packing material for sealing the valve against leakage.

The sleeve 12 is interiorly threaded to receive the threads 15 of the rotatable valve member 16. This member at its inner end is provided with an enlarged hollow head 17 for the reception of a renewable washer or seat 18^a formed of composition or the like. The stem 18 of the valve member 16 is operated by means of an arm 19 having its one end 20 mounted on the stem and its opposite end 21 carrying a float 22. This float is connected to the arm by means of a stem 23 threaded in an adjustable rocker arm 24 which is pivotally mounted upon a bolt or the like 25, the end of the bolt being threaded in a member 26 having a semi-circular opening for receiving the reduced end 21 of the arm 19. By means of this construction, the float and its stem may always be maintained in perfect alignment and the rocker adjusted upon the arm 19.

The float 22 is movable in a secondary or auxiliary tank 27 open at its upper end and its lower end threaded in a base 28. In its preferred embodiment, this base forms part of a casting 29, which also includes the discharge pipe 5, base 30 for an overflow 31, concave valve seat 32 for a ball valve 33, an outlet 34 from the secondary or auxiliary tank 27, and an outlet 35 from the overflow.

The ball valve 33 is mounted upon a stem 36 50 slidably in a guide arm 37 adjustably mounted on a split collar 38 adapted to encompass and be retained on the overflow by means of bolt 39 and nut 40. The guide arm is provided with an adjusting slot 41 in which is a bolt 42. A wing 55

nut 43 clamps the guide arm in adjusted position upon the split collar 38.

The stem 36 is provided with a head or enlargement 44 against the underside of which 5 engages an eye 45 of a lever arm 46 having a hook 47 for receiving the end of the usual tank trip lever and whereby the ball valve 33 may be raised from its seat to permit a flushing of the toilet.

- 10 In the operation of the novel invention, and assuming that the main flush or supply tank is filled to the desired height, a tripping of the tank lever will raise the ball valve 33 to permit a discharge of the accumulated water from the 15 main tank as well as from the auxiliary tank 27 through its outlet 34 into the main discharge pipe 5. When the water has been completely discharged, the ball valve will reseat and the float 22 will drop because of its weight and 20 thereby lower the end 21 of the arm 19, whereby to turn the valve stem 18 and separate the valve parts in the ballcock or valve 8 to permit water to flow from the supply pipe, through the valve and then through the inlet pipe 48. In order to 25 silence the water passing through the inlet the invention comprehends the provision of a muffler 49. This muffler or silencing means comprises a cup or receptacle 50 positioned below and spaced from the discharge end of the inlet pipe, and a 30 skirt 51 concentrically spaced from said cup by means of a plurality of spacers 52. Thus the water flowing from said inlet pipe 48 must discharge into the cup 50, and from there over the sides thereof and downwardly between the cup 35 and overhanging skirt 51.

Also leading from the inlet pipe 48 is a relatively small inlet 53 leading to and permitting the passage of a small amount of water to the overflow 31. This water provides an afterfill for 40 sealing the trap of the bowl.

When the ballcock or valve 8 is opened, the water discharging into the main tank quickly increases in depth until it overflows in the auxiliary or secondary tank 27. The accumulated water in the auxiliary tank will raise the float 45 22, causing the arm 19 to be raised and thereby turn the valve stem 18 to close the ballcock or valve 8.

It will be readily seen from the above description and the disclosure, that the ballcock or valve will be completely open until the tank has 50 been completely filled since the water which trips the valve is overflow from the tank. This permits a filling of the tank in considerably less time than with prior constructions, as well as a minimum wear upon the valve parts which are 55

quickly and fully opened and closed when the ballcock or valve is operated.

By means of the muffler arrangement, the discharged water is silenced. Also the valve construction is much more positive in operation, and 5 by making the discharge pipe from the tank as a casting which also forms the ball seat as well as the base for the overflow and auxiliary tank, a less expensive and more readily assembled construction is produced.

Having thus disclosed the invention, I claim:

1. In a flush tank construction, an auxiliary tank therefor provided with means for controlling the inlet to said flush tank, a ball flush valve, a concave valve seat for said valve, a discharge 15 for the flush water and an outlet from said auxiliary tank to said discharge, the base of said auxiliary tank, valve seat, outlet and discharge being formed of a unit casting.

2. In a valve construction for toilets and the 20 like, the combination of a flush tank provided with an inlet and an outlet for the accumulated water, a valve in the inlet, an auxiliary tank for receiving the overflow from the flush tank, means in the auxiliary tank for operating the 25 valve and adapted to close the valve when the flush tank is filled to the proper depth and the overflow in the auxiliary tank reaches a predetermined level, an outlet from the auxiliary tank, and a single valve for opening and closing both 30 said outlets for controlling the discharge from the flush tank and the auxiliary tank.

3. In a valve construction for toilets and the like having a flush tank, an inlet therefor and a discharge therefrom to the toilet, a valve in the 35 inlet for controlling the quantity of water passing to the tank, an auxiliary tank for receiving the overflow from the flush tank, a float in the auxiliary tank connected to and operating the valve and adapted to close the valve when the 40 overflow in the flush tank reaches a predetermined level, a discharge opening from each of the tanks and a single valve for normally closing both of the discharge openings and draining said flush and auxiliary tanks.

4. In a flush tank construction provided with an inlet and a discharge, an auxiliary tank therefor adapted to receive water when the flush tank is filled to the proper depth, means associated with said auxiliary tank and dependent upon the 50 depth of water therein for closing said valve, a discharge from said auxiliary tank, and a valve member adapted to normally close and retain both said discharges in closed position except when the tank is being flushed.

JOHN T. McGRATH. 55
